(57) **CLAIM**

The ornamental design for a truck bed tray, as shown and described.

DESCRIPTION

FIG. 1 is a perspective view of the present invention.

FIG. 2 is a perspective view of the embodiment shown in FIG. 1

FIG. 3 is a perspective view of the embodiment shown in FIG. 1

FIG. 4 is a front elevational view of the embodiment shown in FIG. 1.

FIG. 5 is a rear elevational view of the embodiment shown in FIG. 1

FIG. 6 is a top-down view of the embodiment shown in FIG. 1

FIG. 7 is a bottom-up view of the embodiment shown in FIG. 1.

FIG. 8 is a right-side profile view of the embodiment shown in FIG. 1; and,

FIG. 9 is a left-side profile view of the embodiment shown in FIG. 1.

In the drawings, the broken lines depict portion of the truck bed tray that form no part of the claimed design. The truck bed in FIG. 1 shown in broken lines is for environmental subject matter only and forms no part of the claimed design.

1 Claim, 7 Drawing Sheets
